(57) **CLAIM**

The shape and ornamental design for a kettlebell, as shown and described.

DESCRIPTION

FIG. 1 is a perspective view of a kettlebell showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a reference figure showing the use of the kettlebell in which the pins are rotated 90 degrees.

The broken lines illustrate portions of the kettlebell which form no part of the claimed design.

1 Claim, 8 Drawing Sheets
